EDMUND BERNARD DOWD, OF CHICAGO, ILLINOIS

FORMING MEANS FOR COMPOSITE COLUMNS AND THE LIKE

Application filed May 21, 1927. Serial No. 193,218.

This invention relates to improvements in forming means for composite columns, beams, and the like, and is an improvement over my co-pending application for means for forming plastic columns, Serial No. 126,144, filed under date of July 31st, 1926.

This invention relates more particularly to forming means for plastic columns and the like, which means include a plurality of interengageable members adapted, when assembled, to outline a beam or column, and to permit the use therearound of any sectional lagging, regardless of the size of the lagging sections relative to the column desired.

In constructing plastically formed columns heretofore, numerous varieties of forms have been used, both of the sectional lagging type and the built-up type. The former type necessitates having on hand lagging sections of various sizes to correspond with the various sizes of columns desired. The built-up type of form is obviously objectionably expensive in time and labor and must be wholly or partially destroyed when removed from a set column.

With these objections in view, it is accordingly an object of this invention to provide means for forming or outlining a plastic column, which means permit the use of any kind or size or lagging therearound.

Another object of this invention is to provide forming means comprising interengageable members adapted to outline a column or beam and to act as reinforcing means therefor.

Another object of this invention is to provide efficient and effective forming and reinforcing means to which the lagging is not attached in any way.

Still another object of this invention is to provide economically manufactured forming means adapted to automatically center lagging with respect to a fabricated steel structure.

A further object of this invention is to

provide forming means of the class described, adapted to provide suitable anchorage for facing or furring if so desired.

A still further object of this invention is to provide forming means which, when assembled, provide accurate gage lines for measuring the structure.

Other and further important objects of this invention will be apparent from the disclosures in the specification and accompanying drawings.

This invention (in a preferred form) is illustrated in the drawings and hereinafter more fully described.

On the drawings:

Figure 1 is a view in elevation, with parts omitted and parts broken away, of a column formed by the device embodying principles of the present invention.

Figure 2 is a half-sectional view taken substantially on line II—II of Figure 1.

Figure 3 is a view similar to Figure 2, showing the device of Figure 1 associated with a reinforcing steel core.

Figure 4 is an enlarged fragmentary view of a portion of Figure 2.

Figure 5 is a distorted view, with parts omitted, taken substantially as indicated by the line V—V of Figure 4.

Figure 6 is a mongrel sectional view showing supporting means for lagging as used with the present invention.

Figure 7 is a sectional view taken substantially along line VII—VII of Figure 4.

Figure 8 is a sectional view taken substantially along line VIII—VIII of Figure 4.

Figure 9 is a vertical sectional view taken substantially along line IX—IX of Figure 4.

Figure 10 is a vertical sectional view taken substantially along line X—X of Figure 4.

Figure 11 is a vertical sectional view taken substantially along line XI—XI of Figure 4.

Figure 12 is a vertical sectional view taken substantially along line XII—XII of Figure 4.

Figure 13 is a vertical sectional view taken substantially along line XIII—XIII of Figure 4.

Figure 14 is a vertical sectional view taken substantially along line XIV—XIV of Figure 2.

Figure 15 is a fragmentary elevational view taken substantially as indicated by line XV—XV of Figure 2.

10 Figure 16 is a fragmentary plan view of a portion of the device disclosed by Figure 3.

Figure 17 is a fragmentary vertical sectional view taken substantially along line XVII—XVII of Figure 16.

15 As shown in the drawings:

As illustrated in the drawings, the present invention is shown set up to form a vertical column, and is assembled in readiness for the pouring of concrete or other plastic material. It is obvious, however, that this invention is equally adaptable for forming beams or the like, in horizontal or oblique positions.

In the illustrated embodiment of this invention there is shown a fabricated steel structure or I-beam 1 to act as a core for the composite column to be formed. At spaced intervals around the steel structure 1, triangular posts 2 are placed, which posts 20 extend the full length of the column. The posts 2, as shown in Figure 1, are held in their desired position by the reinforcing bands 3 hereinafter more fully described. Around the posts 2 and the bands 3, integumentary covering comprising any desired sections of lagging, may be positioned, or, as shown, wooden lagging sections 4 reinforced by angle irons, may be used. It is to be noted, as illustrated in the drawings, 40 the lagging sections 4 need not be of a fixed size corresponding to the dimensions of the column, but may be of any size without detracting in the least from their utility.

The lagging sections 4 are maintained in a 45 useful position by any desired form of clamping means or, as shown in Figure 6, by a movable clamp formed of members 5 hinged together in pairs as shown at 6. The members 5 are dove-tailed at opposite corners of the 50 clamp to fit together and are perforated adjacent the dove-tailing as at 7, whereby plates 8 may be laid over the junction points of the members 5 and secured thereto by pins passing through an aperture 9 in the plates 8 which will be in alignment with one of the 55 apertures 7. If the lagging sections 4 are wider than the column to be formed, blocks 10 are inserted between the sections 4 and the members 5 of the clamp, and thusly 60 lagging of any size may be tightly secured in its useful position.

The bands 3 are each formed of a plurality of members, and comprise, with other members, a plurality of similar unitary reinforcing elements 11 and 11^a, adjustably inter-

engageable. The only difference between the elements 11 and 11^a lies in their positioning, the elements 11^a being inverted relative to elements 11.

Each of the elements 11, for instance, is formed by a stamping process from sheet metal, band iron, or the like, and comprises an angular or channel portion 12 which is slidably engageable with a similar portion on an adjacent element. Adjacent one end 70 of the channel portion 12, and substantially at right angles thereto, and integral therewith is a portion 13 bent upon itself to define a loop 14 at its outermost end, and provided with aligned notches 15 therein. Integral 75 with the portion 13 and angularly bent therefrom is a channel portion 16 having aligned apertures 17 through its sides. Adjacent the bends 18 and 19 as shown in Figure 4, the element 11 is slit and the bottom portion extends outwardly parallel with the portion 13 to define tongues 20. In the portion 12 of the element 11 a part of the channel wall is cut out, as shown at 21, and bent back upon itself to provide an abutment 22 which abuts 80 against the portion 13 to strengthen the same and to prevent any further rearward bending thereof. Figures 7, 8, 9, 10, and 12, illustrate the various cross-sections of the portion 12 of the element 11.

In the formation of one of the bands 3 shown in Figure 1, a pair of elements 11 are positioned with their channel portions 12 in 90 slideable engagement with each other, and to stiffen the structure, are tied in this position by a wire loop 23 (Figure 14) or by equivalent means. Obviously, the elements so secured are similarly formed but differ to correspond to "left" and "right" members. These elements 11 are positioned along opposite sides in the fabricated steel structure 1 and to complete the square, elements 11^a similarly secured together, are placed along the other opposite sides of the structure 1. As shown especially in Figure 4, the notches 15 and channel portion 16 of the member 11 are engaged by corresponding notches and a channel portion of the member 11^a. Through the aligned apertures 17 pins 17^a are inserted 100 to hold the channel portions 16 of elements 11 and 11^a together. To rigidify and center the square band thus formed opposite elements 11 are tied together by a criss-cross wire lacing 24 passing through the loops 14 (Figure 15), and the elements 11^a are tied in a 105 similar manner, thus preventing the respective elements from being forced apart or out of adjustment by the pressure exerted by the plastic material upon pouring.

Angularly bent resilient strips 25 are secured between the extended tongues 20 of the various elements 11 and 11^a by rivets 26, and extend outwardly therefrom adjacent the sides of the posts 2 to which they are removably secured by nails 27. It is to be noted 110

that the strips 25, when affixed to the posts 2, have their outer edges in abutment as shown at 28, which abutment provides an accurate gage line at each corner of a column to be formed, from which gage line accurate measurements of the size of the column may be taken.

In the use or operation of the present invention, the fabricated steel structure 1 having been previously positioned, the corner posts 2 are placed in their respective positions corresponding to the size of the desired column. The bands 3 are then formed around the fabricated steel structure 1 and secured to the corner posts 2 in the previously described manner. In a column of this nature when the plastic material is poured within the lagging, the maximum stress or strain will occur about one-third the height of the column from the bottom thereof, and therefore the bands 3 are usually placed somewhat closer together (Figure 1) at this region of the column and are spaced farther apart near the top of the column. It is to be noted that in positioning the bands 3, due to the engagement of the portions 13 of the elements 11 and 11^a and the wire lacing 24 with the fabricated core structure 1, the posts 2 will be automatically centered with respect to this structure 1. After these bands 3 have been positioned, the lagging sections 4 are placed therearound and clamped as previously explained. Of course, the elements 11 and 11^a, due to their adjustable engagement one with the other at the portions 12 thereof, may be used in the manner herein described, for any and all sizes of columns. After the plastic material has set and the composite column is completed, the clamps and lagging sections are removed, undamaged, and may be used for other columns. When the lagging is removed, the nails 27 are extracted from the posts 2, the outer portions of the angular members 25 are bent normal to the column and the posts 2 are removed. The outwardly extending portions of the members 25, which members will now be straight instead of angular, provide suitable anchorage for facing or furring, if desired. If the facing or furring is not desired, it is a simple expedient to chisel or break off the members 25 adjacent the exterior of the set plastic column.

The elements 11 and 11^a with the wire lacing 24 remain in the column and act as reinforcing steel for the plastic material. As shown in the drawings the posts 2 are triangular in shape with the bases inwardly positioned, and when so placed will leave chamfered corners on the column. Obviously, corner posts having any type of interior configuration may be substituted for the posts 2 without departing from the spirit of the present invention.

As shown in Figures 3, 16, and 17, the present invention is equally adaptable for

use in forming a composite column in which the steel structure comprises circular or spiral reinforcing steel and vertical rods. In Figure 3 there is shown circular reinforcing steel 29 supported by vertical rods 30 which structure acts as a supporting core for the composite column to be formed. The bands 3 are formed of the elements 11 and 11^a and the angular pieces 25 are secured to the posts 2, precisely as previously described herein. However, in this case, the circular reinforcing steel 29 will not permit the elements 11 and 11^a to be tied together by the wire lacing 24, and to prevent the portions 12 of the various elements of 11 and 11^a from sliding one upon the other due to the pressure of plastic material novel means have been provided to fixedly connect the elements in their desired position.

The securing means comprises a strip 31 bent to form an elongated S-hook which engages over the extremities of the portions 12 of the elements 11 and 11^a as shown in Figure 16. A clamping member 32 formed of a strip bent to encircle the elements 11 and 11^a and the S-hook 31, is provided with aligned apertures 33 therein. The clamping strip 32 is held in tight engagement with the elements 11 or 11^a as the case may be and the S-hook 31, by the wire 34 which passes through the apertures 33 and is tied in any convenient place, as at 35. The clamping member 32 when in its tied position abuts the lagging as shown at 36. The lagging sections 4 are positioned in this case in the same manner as previously described herein and the operation is the same in both cases with the exception that in the latter case the clamping member and S-hook 31 must be used while the lacing 24 is omitted.

Obviously, the forming means described herein provide for very economical installation of electrical conduits and outlets within the column, inasmuch as ample space is left between the steel core and the lagging to permit the free and easy installation of electrical contrivances within the column.

From the foregoing it will be apparent that I have provided novel means for forming columns, which means afford obvious advantages over previously known forms. The means disclosed herein are very economically manufactured, are adapted for a two-fold purpose, namely, to act both as forming means, and reinforcing for the column, and permit the use of any desired form of lagging without any damage occurring to the same. Moreover, the means disclosed herein comprising standard units are easily obtainable, and are far more quicker in operation than means heretofore known for a similar purpose.

I am aware that many changes may be made and numerous details of construction may be varied through a wide range without depart-

ing from the principles of this invention and I, therefore, do not purpose limiting the patent granted hereon otherwise than necessitated by the prior art.

5. I claim as my invention:

1. Means for forming a plastic beam or column, including corner supports, and a plurality of bands removably attachable in spaced relationship to said supports to outline said beam or column.
10. 2. In combination with corner supports, an element for adjustable engagement with similar elements to form a reinforcing band, and means engageable by said element for connecting said band to said supports.
15. 3. Means for forming a composite column or beam, including corner supports extending the length of said column or beam, adjustable bands removably secured to said corner supports, and means for maintaining said bands in their adjusted position.
20. 4. Means for forming a composite column, including corner supports, bands, means for attaching said bands to said supports at spaced intervals, whereby said bands outline said column and permit the use of any lagging therewith.
25. 5. Means for forming plastic material around a core to provide a column, including a plurality of reinforcing elements interengageable to form adjustable bands to outline said column, and means held by said elements to provide anchorage for facing or furring.
30. 6. Means for forming a plastic column, including corner supports, adjustable bands to hold said supports in position, means for removably securing said bands to said supports, said means being bendable normal to said column as anchorage for furring when said column has set.
35. 7. As an article of manufacture, an element comprising an angular portion, a portion integral therewith and bent upon itself to define a loop, said element being engageable therefor with similar elements to form reinforcing means.
40. 8. As an article of manufacture, an element formed from sheet material and comprising an angular portion, a portion bent at substantially right angles thereto and being bent upon itself to define a loop at its outermost end, and an angularly bent channel portion integral with said second mentioned portion, said element being adjustably engageable with similar elements to form reinforcing means.
45. 9. As an article of manufacture, an element comprising an angular extended portion, a portion at substantially right angles thereto having a loop therein, an angularly bent channel portion on said second mentioned portion, and spaced projections on said second mentioned portion adapted to engage an object therebetween, said element being adjustably

engageable with similar elements to provide reinforcing means.

10. In combination with lagging, means for forming a composite column or the like, including corner supports, adjustable bands comprising a plurality of interengageable elements, and means for removably securing said bands to said supports.

11. Means in combination with any desired lagging for forming a composite column or the like, including elements adjustably interengageable to form reinforcing bands, supports, and means for connecting said bands to said supports, said elements each comprising a channel portion, and a notched portion at an angle thereto, said portions engageable by similar portions on a similar element.

12. Means for forming a composite column, including supports, adjustable bands to outline said column, and means engageable by said bands to removably secure said bands to said supports, said means being attachable to the exteriors of said supports and outwardly bendable to provide anchorage for facing and the like.

13. Means for forming a plastic column, said means including corner supports, adjustable bands formed by interconnecting a plurality of elements, angular members held by said elements to secure said bands to said supports, said members being abuttable at the outer corners of said supports to define a gage line.

14. Means for forming a plastic column having a steel core therein, including a plurality of elements interengageable to form adjustable bands around said core, supporting members removably secured to said bands, and means for retaining said bands in their adjusted position, said elements each comprising a channel portion for slidably engagement with a similar portion on an adjacent element, a notched portion angularly related to said channel portion and a second channel portion angularly related to said notched portion, said two last mentioned portions engageable by similar portions of a transversely positioned element.

15. As an article of manufacture, an element for adjustably engaging with similar elements to form reinforcing means, said element comprising a portion bent upon itself, both sides of said portion being split adjacent one end of said portion, the ends of said portion on one side of said split defining gripping flanges, and the ends of said portion on the other side of said split being angularly bent away from each other to define angularly disposed channel members.

16. Means for forming plastic material to provide a column, including corner supports, adjustable bands for generally outlining said column, and means associated with said bands for attaching the same in spaced rela-

17. Means for forming plastic material to provide a column, including corner supports, adjustable bands removably engageable with said corner supports to generally outline said column and permit the use of any suitable lagging therearound, and projecting means on said bands for abutting said lagging intermediate said corner supports.

In testimony whereof I have hereunto subscribed my name at Chicago, Cook County, Illinois.
